METHOD OF FRACTIONATING FATTY PITCHES

Leo Garwin, Oklahoma City, Okla., assignor to Kerr-McGee Oil Industries, Inc., a corporation of Delaware

No Drawing. Filed May 7, 1958, Ser. No. 733,502

9 Claims. (Cl. 260—97.6)

This invention relates to a method of separating a high softening point resinous material from fatty pitches as a fluid phase. This invention further relates to a method for solvent treating fatty type pitches to separate at least a resinous material having a softening point of at least 170° F. More specifically, this invention relates to a method for solvent extracting fatty type pitches with hydrocarbons containing from 5 to 8 carbon atoms when saturated and from 4 to 7 carbon atoms when unsaturated.

The hydrocarbons of 1 to 8 carbon atoms are known to be useful solvents for treating animal and vegetable oils and/or fats. In fact, propane, pentane and hexane are used in a number of commercial installations to treat fats and oils to remove color bodies, to obtain vitamin concentrates and to produce edible and industrial oils having improved color, odor and related stability properties.

In addition to the above, the prior art further teaches that the results achieved with the individual hydrocarbons are essentially the same. In general, the lighter hydrocarbons, for instance propane, appear to be preferred for treating oils and fats per se and the heavier hydrocarbons, for example, pentane and hexane, are preferred for extracting the oils from meal cake, i.e. crushed seed pulp. This preference does not appear to be based on any difference in the fractionation effect of these solvents but on the ease with which they may be adapted to the particular product being treated or for other reasons.

Even though the solvent treatment of fats and oils is quite popular, a considerable volume of fats and oils is still subjected to distillation to produce improved edible and industrial products. The bottoms from the distillation process are generally referred to as fatty pitches and specifically are referred to as the pitch of the specific oil or fat subjected to distillation, for example, tall oil pitch, soybean pitch, stearine pitch, etc.

These pitches have properties which are dependent to a certain extent on the severity of the distillation to which the fat or oil is subjected, and consequently, may be either soft or hard, friable materials.

The pitches have a number of uses, and these uses result primarily from the low price of the pitches. For instance, one use of the pitches is in the manufacture of bituminous tile or floor coverings. Although a considerable volume of the fatty pitches is used for floor coverings, the fatty pitches impart certain properties to the finished product which limit its commercial acceptance. For example, the soft pitches generally contain sufficient carboxylic groups to reduce the alkali resistance of the floor covering and, in addition to this objectional feature, the soft pitches require the use of an inordinate amount of high softening point bituminous materials, for example, blown asphalt, gilsonite, asphaltic resins and asphaltenes, to give the floor covering sufficient indentation resistance and hardness. The use of large amounts of high softening point bituminous material lowers the pigmentation response of the binder, increasing the pigment cost and the cost of the finished floor covering.

2

On the other hand, if hard and friable fatty pitches are used, such fatty pitches normally have been subjected to cracking conditions during their production, and their chemical structure has undergone a change as a result of polymerization. Some of the more valuable oils have been lost due to this molecular change upon cracking and polymerization.

When the hard fatty pitches are used in the manufacture of floor coverings, the amount of soft asphalt has to be increased and the resulting tile may have undesirable temperature susceptibility properties and low resistance to oxidation.

It is readily apparent to those skilled in this art that the formulator must compromise on the properties desired in the finished floor covering when using the fatty pitches in his formulation.

Therefore, an object of this invention is to provide a method for solvent treating fatty pitches to produce a relatively high softening point resin which is free of some of the aforesaid undesired properties and to produce a light fraction containing no resinous materials.

It is a further object of this invention to provide a method of separating a high softening point resinous material from fatty pitches as a fluid phase.

Another object of this invention is to enable the processors of fats and oils to upgrade distillation bottoms and thus increase the market value and acceptance of said products.

Still another object of this invention is to provide an economic method for solvent treating fatty pitches to fractionate them into a heavy resinous fraction having a relatively high softening point and a light fraction, and to carry out the separation of said fractions while in the fluid phase.

Still other objects and advantages of this invention will be apparent from the ensuing description and the appended claims.

In accordance with these objects, a fatty pitch is intimately contacted with a suitable hydrocarbon solvent, having the characteristics described hereinafter, at elevated temperature and pressure conditions which give the hydrocarbon a density of the prescribed magnitude. A further aspect of this invention comprises treating a fatty pitch with at least two volumes of a hydrocarbon solvent of the prescribed number of carbon atoms for each volume of pitch with the temperature and pressure conditions being adjusted to separate a heavy and a light fraction as fluid phases. An additional aspect of this invention relates to the discovery that the high molecular weight hydrocarbons, i.e., those having between about 5 to 8 carbon atoms, have a different fractionating effect on the fatty pitches than that exhibited by propane.

For example, propane separates from the soft fatty pitches a relatively soft heavy fraction, but pentane, on the other hand, separates from the same pitch a heavy fraction having a softening point of approximately 180-200° F. and higher. Pentane and the higher molecular weight hydrocarbons, i.e. those containing up to about 8 carbon atoms, separate not only a high softening point resinous fraction but separate said fraction as a fluid phase, and this prevents the plugging of the fractionation system thereby allowing continuous operation of the fractionator.

To specifically illustrate this difference between the action of propane and pentane on fatty pitches, a tall oil pitch was treated separately with these solvents at room temperature. It was found that the heavy fraction obtained with propane had a softening point of about 120° F. but the pentane separated fraction had a softening point of 180-210° F. Also, it was observed that the pentane derived fraction separated as a solid precipitate which

would plug the fractionation tower and the heavy fraction withdrawal line.

When the temperature of treatment was raised, it was observed that the yield of the propane heavy fraction from tall oil pitch increased but the softening point tended to be lower. On the other hand, it was observed that at a temperature of 200° F. pentane separated from tall oil pitch a heavy fraction having a softening point of at least 170° F. and the yield was essentially the same as that obtained at room temperature with pentane. This is contrary to the teachings of the hydrocarbon solvent treating art. Normally it is expected that the softening point of the heavy fraction will decrease and its yield increase with increasing temperature.

It was also discovered that the light fraction (having a softening point of about 100° F.) from the high temperature treatment with pentane could be further fractionated to give a secondary heavy fraction having a softening point approximately the same as that of the heavy fraction obtained by propane treatment. This means that the fatty pitches such as tall oil pitch may be fractionated by means of the higher molecular weight solvent hydrocarbons into a high softening point friable resin and a low softening point resin having good ductility properties. The light oily fraction obtained by this process has interesting possibilities as a constituent of paints and other protective coatings.

As indicated previously, the hydrocarbons suitable for use in my invention may be either saturated or unsaturated in nature. The saturated hydrocarbons have from 5 to 8 carbon atoms, inclusive, and may be straight chain, branched chain or cyclic in nature. The unsaturated hydrocarbons useful in my invention contain from 4 to 7 carbon atoms and likewise may be straight chain, branched chain or cyclic in nature. The preferred unsaturated hydrocarbons are the mono-olefins. It should be noted that the cyclic hydrocarbons are not as well suited for this invention as the others because the cyclic hydrocarbon densities at a given temperature and pressure are generally higher than those of their corresponding straight chain homologues, and the cyclic compounds thus require a higher temperature to obtain the desired fractionation.

In general, the temperature must be at least about 200° F. and less than the paracritical temperature to separate the heavy resinous fraction as a fluid phase. The paracritical temperature is generally considered to be from 50° F. below the critical temperature to above the critical temperature.

It should be noted that tall oil pitch, although not generally classified as being derived from either vegetable or animal fats or oils, has chemical and physical properties which would certainly properly include it in a fatty pitch category along with the pitches derived from soybean oils, tallow, coconut oils, etc.

The volume ratio of solvent to pitch is critical. If the volume ratio of solvent to pitch is not at least 2 to 1, no phase separation occurs. In fact, the selectivity is very poor at volume ratios between about 2 to 1 and 4 to 1. Therefore, it is preferred that at least 4 volumes of solvent be used for each volume of pitch to increase the selectivity and thus insure that optimum yields of the desired fractions will be obtained. Generally, 5 to 10 volumes of solvent to each volume of pitch will be used in the practice of this invention although at times the ratio may be even as high as 20 to 1 or higher.

Although the conditions necessary to separate the fractions in accordance with the spirit of this invention are obtained by adjusting the temperature, pressure and solvent to pitch ratio, a definite relationship between the temperature and pressure is necessary to accomplish the result. For example, the pressure must be at least equivalent to the equilibrium pressure of the solvent at the separation temperature and sufficient to give the solvent an effective density within certain prescribed limits. Nor-

mally the heavy fraction having a softening point of at least 170° F. is obtained as a fluid phase at a solvent density of at least 0.45 g./ml. and less than 0.60 g./ml. The preferred solvent density for effecting the separation of a heavy fraction having a softening point of at least 170° F. is between about 0.48 and 0.55 g./ml.

The density of the solvent at which a secondary heavy phase may be separated is between about 0.25 g./ml. and 0.45 g./ml. Generally, the secondary heavy fraction will have a softening point between 100° and 135° F. and a light color.

Although the solvent is readily recovered from the separated fractions by flashing, distillation, etc., a preferred method of recovering the solvent comprises raising the temperature of the solvent mixture above the critical temperature of the solvent and adjusting the pressure to give the solvent a density less than about 0.25 g./ml. Under these conditions the solvent and separated fraction demix and the solvent, free of any dissolved pitch fractions, may be removed overhead from the pressure vessel. This method of recovering the solvent offers a number of advantages over flashing or distillation. For example, the heat required is about half that required for flashing, and the cooling water requirements are also considerably lower. Pumping capacity and costs are reduced.

My invention is further illustrated by the examples.

Example I

A sample of crude tall oil, Acitol-C, a product of Arizona Chemical Company, was used in this experiment. This particular crude tall oil was characterized by the following analysis:

Color ratio	0.0046
Color	Dark
35 Acid No.	170
Rosin acids	percent 42
Unsaponifiables	do 7
Iodine No.	170

One volume of this crude tall oil was intimately mixed with 10 volumes of pentane and let stand at ambient temperature, approximately 85° F. The light phase was decanted from the heavy phase. The separate fractions were heated to remove the pentane. The yield of light phase was 98.2% by weight and the yield of heavy phase was 1.8% by weight. The color ratios of the light fraction and the heavy fraction were 0.0015 to 0.111 respectively.

The color ratios, as used above, were obtained from readings on a Klett-Summerson photoelectric colorimeter using a green filter. The samples were diluted $\frac{1}{3200}$ in aromatic naphtha (Bronoco Hi-Sol #20) and the reading compared with that for gilsonite, which was taken as unity.

When propane was substituted for pentane in the treatment of this same crude tall oil, the yields of heavy and light fractions were of the same magnitude, i.e., there is obtained a very low yield of heavy fraction and the great bulk of the stock remains dissolved in the solvent. It should be noted that comparable yield results are reported in the published literature for other animal and vegetable oils when treated with these same solvents.

Example II

A tall oil pitch, a bottom product of the distillation of the crude tall oil, showed the following properties:

Acid No. 68, color ratio 0.035, semi-solid tacky appearance.

One volume of this tall oil pitch was placed in a bomb and 10 volumes of propane was added. The bomb was 70 rocked to intimately contact its contents and then was allowed to stand. The ambient temperature was about 85° F. and the pressure of the bomb was 140 p.s.i.g. Two phases formed on standing. These were separated by extruding the heavy phase through the valve on the bottom of the bomb. The heavy phase was fluid within

the vessel and extruded readily. The heavy fraction was heated to remove the last of the solvent. The heavy fraction was obtained in a yield of 71.6% by weight and had the following characteristics: Softening point 125° F., color ratio of 0.067. The light fraction, after solvent removal, was an oil having a color ratio of 0.012.

Example III

The experiment of Example II was repeated using pentane instead of propane. The heavy fraction was present in the contacting vessel as a precipitate instead of as a fluid phase. The phases were separated by decantation of the light phase. The yield of heavy fraction was 18%. This fraction had a softening point of 181° F. and a color ratio of 0.101. The light fraction had a color ratio of 0.016.

Example IV

The experiment of Example III was repeated except that the temperature of the bomb was raised to 200° F. The bomb pressure at this temperature was 60 p.s.i.g. The heavy phase was present within the bomb as a fluid phase and extruded very readily through the valve in the bottom of the bomb. The heavy fraction, obtained in 29.3% weight yield, had a softening point of 191° F.

The light phase was given a further treatment at a higher temperature to separate a light resinous fraction. The temperature was raised to 390° F. The bomb pressure at this temperature was 525 p.s.i.g. The secondary heavy phase was present within the bomb as a fluid phase and was extruded very readily from the vessel. The yield of light fraction was 40.9% by weight and the yield of the secondary heavy fraction (soft resins) was 29.5% by weight. The secondary heavy fraction had a softening point of 132° F. The light fraction was a reddish oil.

When hexane was substituted for pentane, the yield of primary heavy fraction tended to be less and the softening point tended to be higher.

What is claimed is:

1. A method of separating a high softening point resinous material from fatty pitches as a fluid phase comprising treating each volume of pitch with at least 2 volumes of a hydrocarbon solvent selected from the class consisting of saturated aliphatic hydrocarbons having 5 through 8 carbon atoms, inclusive, and mono-olefin hydrocarbons having 4 through 7 carbon atoms, inclusive, at elevated temperature and pressure, the temperature being at least 200° F. and less than the para-critical temperature of the solvent, the pressure being at least equivalent to the equilibrium pressure of the solvent at this temperature and being adjusted to provide a solvent density greater than 0.45 g./ml. and less than 0.60 g./ml. to produce a fluid heavy phase and a lighter phase and separating said heavy phase while fluid from the lighter phase to obtain a high softening point resin.

2. The method of claim 1 wherein the fatty pitch is tall oil pitch.

3. The method of claim 1 wherein the hydrocarbon solvent is pentane.

4. A method of separating a high softening point resinous material from fatty pitches as a fluid phase comprising treating each volume of fatty pitch with at least 4 volumes of a hydrocarbon solvent selected from the class consisting of saturated aliphatic hydrocarbons having 5 through 8 carbon atoms, inclusive, and mono-olefin hydrocarbons having 4 through 7 carbon atoms, inclusive, at elevated temperature and pressure, the temperature being at least 200° F. and less than the paracritical temperature of the solvent, the pressure being at least equivalent to the equilibrium pressure of the solvent at this temperature and being adjusted to provide a solvent density greater than 0.48 g./ml. and less than 0.55 g./ml. to produce a fluid heavy phase and a lighter phase, and separating said heavy phase while fluid from the lighter phase to obtain a high softening point resin.

5. The method of claim 4 wherein the fatty pitch is tall oil pitch.

6. The method of claim 4 wherein the hydrocarbon solvent is pentane.

7. A method of separating fatty pitches into at least two fractions wherein all fractions separate as fluid phases and the heaviest fraction has a softening point of at least 170° F. comprising treating each volume of fatty pitch with at least 2 volumes of a hydrocarbon solvent selected from the class consisting of saturated aliphatic hydrocarbons having 5 through 8 carbon atoms, inclusive, and mono-olefin hydrocarbons having 4 through 7 carbon atoms, inclusive, elevated temperature and pressure, the temperature being at least 200° F. and less than the paracritical temperature of the solvent, the pressure being adjusted to provide a solvent density greater than 0.45 g./ml. and less than 0.60 g./ml., separating the resulting fluid heavy phase while fluid from the resulting lighter phase to obtain a resinous fraction having a softening point of at least 170° F., adjusting the temperature and pressure on the lighter phase to provide a solvent density less than 0.45 g./ml. and greater than 0.27 g./ml. to produce a secondary fluid heavy phase and a secondary lighter phase, and separating said secondary heavy phase while fluid from the secondary lighter phase to obtain a secondary resinous fraction and a secondary phase containing pitch oil.

8. The method of claim 7 wherein the fatty pitch is tall oil pitch.

9. The method of claim 7 wherein the hydrocarbon solvent is pentane.
